UNITED STATES PATENT OFFICE.

GRACE WEED MARSHALL, OF BINGHAMTON, NEW YORK.

DEVICE FOR USE IN PLAYING DUPLICATE WHIST.

Application filed April 4, 1922. Serial No. 549,423.

To all whom it may concern:

Be it known that I, GRACE WEED MARSHALL, a citizen of the United States, of Binghamton, in the county of Broome, in the State of New York, have invented new and useful Improvements in Devices for Use in Playing Duplicate Whist, of which the following, taken in connection with the accompanying drawings, is a full, clear, and exact description.

This invention relates to a new and useful device for use in playing duplicate whist or other card games.

One of the objects of the invention is to dispense with the trays ordinarily employed and to provide in place thereof, simple, compact and inexpensive holders for receiving and preserving the different hands as they are played, and retaining the order of the same.

A further object of the invention consists in providing an individual holder for each player, which holder shall contain all the hands held by that particular player during the entire game, thereby eliminating the inconvenience of changing the usual trays during the game.

A further object of the invention consists in providing a holder for the hands of the player that shall lie substantially flat upon the table before the player without causing inconvenience during the play of the hand, and is especially adapted to auction bridge for the reason that it is flat enough to allow the exposed hand of one player to lie flat upon it if necessary.

A further object consists in the provision of a flexible device of the character described comprising a series of overlying or over-lapping pockets for the reception of the individual hands of each player.

A further object consists in the provision of such holder with a series of indicators or indicating indicia, which show the position of the dealer of any hand during the entire game.

A further object consists in providing a device for duplicate whist which may, at the beginning of the game, contain the required number of complete packs for the entire game, each pack placed in correct position with relation to the dealer, as shown by the indicator.

Other objects and advantages relate to the details of form and construction of the de-

vice, all as will more fully appear from the following description, taken in connection with the accompanying drawings, in which:

Figure 1 is a top plan view of a whist table having devices of my invention placed thereon in proper relation.

Figure 2 is a top plan view of one of such devices.

Figure 3 is a bottom plan view of the same device.

Figure 4 is an enlarged section of a portion of one of the devices showing the method of forming the over-lapping pocket.

Figure 5 is a view of a different form of the invention.

Figure 6 is a top plan view of a modified form.

Figure 7 is a longitudinal sectional view of the device of Figure 5.

Figure 8 is a top plan of another modified form.

Figure 9 is a longitudinal sectional view of the device of Figure 7.

The holder, or device of this invention, may be made of cloth, leather or other suitable material, but is preferably of some flexible material, permitting its adaptation to different forms, altho that is not essential to the broader aspect of the invention.

The device, as shown in Figures 1 to 4, comprises a plurality of pockets or receptacles preferably in multiples of four, arranged in partially over-lying or overlapping relation. Each pocket or receptacle, consists of top and bottom pieces which lie substantially flat when there are no cards within the pockets, and each pocket is preferably of a sufficient size to admit a hand of cards.

The bottom and two sides of each pocket are closed, and the top or fourth side open to admit the cards. In the particular illustration here shown, the pockets are slightly less in depth than the width of the cards and a little wider than the length of the cards.

In the particular showing of the drawings here the pockets overlap substantially one-half their width. This permits the production of a compact device without materially thickening the same. Further, this overlapping position of the pockets helps to retain the cards therein and tightens the pocket about the preceding hand by filling up whatever slack is allowed in the construction of the pocket.

115

As there never need be more than three hands which overlap at any one point, the combined thickness of the cards and the holder when filled is less than the thickness 5 of a complete pack. These pockets may be formed and constructed in any suitable manner and may be made in groups of one or more pockets, and then assembled in the manner shown, and secured together by 10 stitching or otherwise or they may be arranged in a circle, as indicated in Figure 5 and there secured together in any suitable manner.

However, it is preferable to construct the 15 pockets and arrange the same in the manner illustrated in Figures 1 to 4.

As shown, the pockets are all formed of a single strip of material of suitable width, which is bent to form overlapping and overlying portions, as best indicated in the section of Figure 4. The opposite side edges 20 of this single strip from which the front and back portions of the pockets are formed are secured together, and preferably at the same time are secured to a backing or base 25 member which is adapted to lie flat upon the table. As illustrated in Figures 1 to 4 the device consists of 12 pockets which bear for the purpose described indicating numbers 30 from 1 to 12 inclusive. These pockets, as stated, are formed from a single strip —1— of suitable material, such as cloth, that is of a flexible nature, permitting its accommodating itself to various surfaces in various 35 forms, altho it is not essential that flexible material be used. This strip of material doubled and redoubled to form the pockets as indicated in Figure 4, has its opposite edges secured to each other where they lie 40 in contiguous relation and to the backing member —2— by stitching, so as to form a firm, substantial device. This backing or base member —2— may, as shown, be formed with a slit —3— which permits the insertion 45 of a score card or other device in the pocket —4— formed by means of a patch member —6— secured to the inner surface of the base member —2— in any suitable manner, as by stitching.

50 Preferably, the device includes in combination with the pockets for holders, a series of indicia, or indicators which may be made of insets or may consist of letters attached to or stamped on the holder to determine the position of the dealer of each hand, as for instance, the letter D, which in the illustration here used is employed to indicate the position of the dealer of a particular hand.

60 The holders are placed on the table, as indicated in Figure 1 and the position of each dealer is indicated opposite the number of that particular hand by means of a series of indicators arranged on the holders in rotation. As there indicated, each device indi-

cates the particular player which is to use that device, as for instance, the devices are identified by letters A, B, X and Y, and as shown A deals the first, fifth and ninth hands, whereas B deals the third, seventh and eleventh hands, X the second, sixth and tenth hands, and Y the fourth, eighth and twelfth hands. As before stated, each pocket is numbered in sequence to identify the particular hand that is to be placed in that pocket, and where twelve pockets are formed in each holder, the pockets may be numbered in any suitable sequence, as for instance, 1 to 12 inclusive. When the desired number of hands have been played, 80 each holder is moved to the left or the otherwise, and the player then having holder marked A holds the position of dealer for the hands, one, five, nine, and the other players have their particular dealing time 85 indicated upon the respective holders in front of the player.

To avoid the delay caused by procuring a new pack of cards for each deal, the entire number of packs may be prepared before the game and each pack placed in a pocket marked by the sign indicating the particular deal of the person having that device, as indicated in the drawing by the letter D. 95

The invention here may be said to consist broadly in a device of the character described, and comprises a series of overlapping pockets for the reception of cards, but in addition thereto, as a preferred character of device, the invention comprises a flexible substantially flat holder of that character which embodies a series of overlapping pockets, and in combination with such a device, the utilization of indicia for indicating the particular sequence of hands to be played or having been played, in addition to indicia as showing what hands should be dealt by each person having one of the devices. 100 105 110

In Figure 5 a modified form of device is illustrated in which the pockets —1— are arranged concentrically upon a circular base member —2—. In Figures 6 and 7 a form of device is shown in which the pockets are formed by securing separate pieces —7— of suitable material as cloth, leather, etc., of desired size, to a base member —2— by stitching along the bottom and edges of the pieces or wherever desired to form separate 115 120 overlapping receptacles for the cards.

In Figures 8 and 9 I have illustrated a different form in which separate pockets or receptacles —8— are secured to a base member —2—. These pockets —9— may be formed in any suitable manner and may be secured to the base in overlapping or overlying relation by any suitable means as stitching to form separate receptacles for receiving cards. 125 130

Altho I have shown and described specific forms and constructions of devices as illustrative of embodiments of my invention, I do not desire to limit myself to the details 5 of form, arrangement or construction of the device, as various changes may be made without departing from the invention, as set forth in the appended claims.

I claim:

10 1. A card apparatus comprising an individual card holder for each player, each holder comprising a series of over-lapping pockets, and each holder having indicia indicating the dealing time of the player using 15 that holder.

2. A card apparatus comprising an individual card holder for each player, each holder comprising a series of over-lapping pockets, each holder having its respective 20 pockets identified by the same indicia, and each holder having indicia indicating the dealing time of the player using that holder.

3. A card holder comprising a single strip of flexible folded material having its contacting edge portions secured together to 25 form a series of card-receiving pockets, and a flexible backing member of a width substantially equal to the width of said pocket-forming strip, and having its opposite longitudinal edges secured to said strip.

30 4. A card holder comprising a single strip of flexible folded material having its contacting edge portions secured together to form a series of over-lapping card-receiving 35 pockets, and a flexible backing member of a width substantially equal to the width of said pocket-forming strip, and having its opposite longitudinal edges secured to said strip.

5. A card holder comprising a single strip 40 of flexible folded material having its contacting edge portions secured together to form a series of over-lapping card-receiving pockets, and a base member of a width substantially equal to the width of said pocket-forming strip and having its opposite longitudinal edges secured to said strip, and a pocket formed in connection with said base member.

45 6. A card holder comprising a flexible 50 backing and a series of overlapping card receptacles each secured to the base by

stitching extending along the opposite edges of the receptacles.

7. A duplicate whist card holder of substantially flat form comprising an elongated 55 strip of flexible material having a plurality of transverse folds forming a series of overlapping pockets arranged in stepped relation, and stitching extending longitudinally of the card-holder at the opposite edges 60 thereof, and connecting each pocket to its overlapping pockets at overlapping portions.

8. A duplicate whist card holder of substantially flat form comprising an elongated 65 strip of flexible material having a plurality of transverse folds forming a series of overlapping pockets arranged in stepped relation, stitching extending longitudinally of the card-holder at the opposite 70 edges thereof and connecting each pocket to its overlapping pockets at overlapping portions, and a backing member of a length substantially equal to the length of the holder 75 and having its edges bent around the opposite edges of the pockets, and stitched longitudinally to the opposite edges of the pockets at the front of the holder.

9. A duplicate whist card holder comprising a plurality of over-lapping pockets arranged in stepped relation, means for connecting each pocket to its overlapping 80 pockets at over-lapping portions, and a backing member of a length substantially equal to the length of the holder and having 85 its edges bent around the opposite edges of the pockets, and stitched longitudinally to the opposite edges of the pockets at the front of the holder.

10. A duplicate whist card holder comprising a plurality of flexible over-lapping pockets arranged in step relation, a flexible backing member of a width substantially equal to the width of the pockets and stitching closing the pockets at opposite ends and 90 connecting each pocket to its overlapping pockets at overlapping portions and to the 95 backing member.

In witness whereof I have hereunto set my hand this 29th day of March 1922.

GRACE WEED MARSHALL.
